UNITED STATES PATENT OFFICE.

JAMES S. GRANT, OF SAN FRANCISCO, CALIFORNIA.

PROPELLER FOR VESSELS.

SPECIFICATION forming part of Letters Patent No. 634,574, dated October 10, 1899.

Application filed August 2, 1899. Serial No. 725,923. (No model.)

To all whom it may concern:

Be it known that I, JAMES S. GRANT, a citizen of the United States, residing in the city and county of San Francisco and State of California, have invented certain new and useful Improvements in Propellers for Vessels; and I do hereby declare the following to be a full, clear, and exact description of said invention, such as will enable others skilled in the art to 5 to which it most nearly appertains to make, use, and practice the same.

My invention relates to that class of propellers for vessels in which the entire propeller is submerged below the surface of the 15 water and in which the paddles or blades are arranged to feather when moving in one direction and to act squarely against the water when moving in an opposite or reverse direction.

20 In my improved propeller the paddles or blades are placed one above and the other below a horizontal plane drawn through the axis about which they move, and instead of revolving in a circle about said axis they reciprocate back and forth in the arc of a circle, 25 acting against the water as they move in one direction and feathering so as to cut and move through the water with little resistance as they move back in the reverse direction, 30 all as hereinafter more fully described.

Referring to the accompanying drawings, Figure 1 is a perspective view showing a pair of my reciprocating propellers mounted at the opposite ends of a shaft. Fig. 2 is a vertical section of one of the hinged blades or 35 paddles and the projecting angular stop. Fig. 3 shows the edge of one of the paddle-bars, and Fig. 4 shows the application of my propeller as a side propeller for a vessel.

40 A is the propeller-shaft, which is driven by a crank connection at B or in any other suitable way. The ends of this shaft project through the sides of the vessel at a sufficient distance below the water-line to keep the paddles of the propellers submerged below the 45 surface of the water at all times. The extremities of the shaft may be supported in a box on an outside beam or timber D, or they may be left free without any support. On 50 each end of this shaft outside the vessel I secure a propeller, which consists of two par-

allel rods, bars, or plates C C, of equal length, secured firmly and fast at their middles to the shaft. In practice I shall usually employ wide plates or castings, which are 55 straight on one edge and which are made circular on their opposite edges, the curve commencing at the front straight edge at one end and continuing around to the front straight edge at the opposite end, in which case the 60 plates will be widest at the straight edges and gradually tapering to a knife-edge at the curve. I prefer to employ this form of bar, because it possesses great strength and its sharp edge and tapering body present very 65 little resistance in moving through the water; but it will be evident that any form of bar of sufficient strength can be used in the construction of my propeller. In the following description I will call this straight flat edge 70 the "front" and the curved edge the "rear" of the plates.

At each end of each of the bars or plates C is an angular arm or projection E, which either forms a part of the bar or plate or is securely 75 fastened to it. These projections or arms extend beyond the front or straight faces of the bars or plates C at an acute angle to the plane of the face. A blade or paddle F extends across the front of the plates or bars C 80 C at each end of the propeller, and the edge of each blade or paddle, which is adjacent to to the angle between the flat faces of the bars or plates and the projection E, is connected by a hinge or loose joint g with the plates, so 85 that the blade or paddle will swing freely on the hinge or joint, so as to either lie flat against the front of the bars or plates or when swung outward will bear against the under faces of the projections in a line tangential to the circle which the hinged edge describes. The 90 free edges of the blades or paddles will then always point toward the shaft A.

In the operation of this propeller the power 95 for driving the propeller is applied with a reciprocating movement, so as to carry the blades through an arc somewhat less than a half-circle, so as not to encounter the dead-center of the crank movement. This causes the blades or paddles to open and close automatically in accord with the direction of their movement. For instance, in making the 100

stroke in one direction the pressure of the water will close one of the paddles or blades, so that it lies flat against the front of the bars C and acts against the water in front of it as a propeller, while the opposite blade or paddle by the same movement is thrown back against the arms or projections E, so as to present its edge to the water, and it will therefore move through the water during this stroke with very little resistance. On the reverse stroke the two blades reverse automatically—that is, the one that feathered during the previous stroke will be thrown up against the front of the bars C, so as to act as the propeller, while the one which acted as the propeller during the previous stroke will be feathered automatically, and so on through each stroke or movement of the shaft. These positions are plainly shown by the dotted lines 20 in Fig. 3. The device may also be used as a stern propeller.

Having thus described my invention, what I claim, and desire to secure by Letters Patent, is—

25 1. A submerged propeller for vessels consisting of two or more parallel bars or plates secured at their middles to the propeller-shaft; a blade or paddle loosely hinged at its outer edge to each extremity of said parallel bars,

30 said blades or paddles being placed on the same side of the bars or plates and adapted to close flat against the front edge of the bars or plates when their free edges are pressed inward toward the shaft; a stop or projection 35 connected with said arms and adapted to arrest the outward movement of the free ends of the blades or paddles in a line tangential to the circle described by said blades, and means for producing a reciprocating movement of said propeller-shaft, substantially as 40 described.

2. In a submerged propeller for vessels; vertical plates for supporting the paddles, said plates having a wide front edge and tapering on each side toward the rear edge; projections at each end of the front edges projecting inward at an angle to the plane of the front edge, and blades or paddles hinged loosely at one edge in the angle formed by the front edge and the projection, substantially as described.

In witness whereof I have hereunto signed my name, in the presence of two witnesses, this 21st day of April, A. D. 1899.

JAMES S. GRANT.
